UNITED STATES PATENT OFFICE.

SAHATIEL G. MANDALIAN, OF NORTH ATTLEBORO, MASSACHUSETTS.

COAT-OF-MAIL METALLIC MESH FABRIC.

Application filed July 26, 1928. Serial No. 295,523.

My invention relates to metallic mesh fabric of the "fish scale" or "coat-of-mail" type.

Heretofore the use of this type of mesh fabric was limited in use to very few articles, and even in the arts wherein it had utility its application was limited to employment only in conjunction with articles peculiarly constructed for its incorporation.

The edges of the fabric were so uneven, unsightly, and excessively flexible as not to be utilizable in the construction of bracelets, bands, girdles, belts, anklets, and the like; and even when used in the construction of mesh bags special construction of the jaws of the latter was required to conceal or attach the edges of the mesh fabric thereto.

The essential objects of my invention are to enable this type of fabric to be universally used in the construction of articles similar to and including all those above referred to and others, and without the necessity of concealment of the edges or any special construction of any article to which the fabric is to be applied, to render the fabric sightly; and to effect these ends in a structure inexpensive to make and possessing the desired degree of flexibility.

To the above ends essentially my invention consists in such parts and in such combinations of parts as fall within the scope of the appended claims.

In the accompanying drawings which form a part of this specification:—

Figs. 1 and 2 are a front elevation and a side elevation respectively of a fabric of the coat-of-mail type embodying my invention;

Figs. 3 and 4, sections of the same on lines 3—3 and 4—4 respectively of Fig. 1;

Fig. 5, a perspective view of the blank from which a binding unit is ultimately bent;

Figs. 6 and 7, obverse and reverse views respectively of the blank partially bent, and engaging two rings;

Fig. 8, a fragmentary rear elevation of the fabric showing certain of the binding units thereon only partially engaged;

Figs. 9 and 10, modified forms of my invention;

Fig. 11, a plan view of an unbent blank of a corner binding unit; and

Fig. 12, a rear perspective view of the same after engagement with a ring link.

Like reference characters indicate like parts throughout the views.

The mesh fabric strip or piece 14, which is of a flexible character, is composed of parallel rows of thin metal ring links 15. Between the rows of ring links are alternating rows of flat cruciform links or plates 16, each of which has four corner prongs 17 rearwardly bent into loops 18 and converging at the rear of the plates. Two prongs or loops of each cruciform link loosely engage two ring links of an upper row of the latter, and its two opposite prongs or loops similarly engage two ring links of a lower row of the latter. Thus all four edges of the fabric piece 14 are composed exclusively of ring links 15 disposed adjacent each other with no portions of the cruciform links projecting therebetween.

It will be noted that each edge of the fabric piece 14, formed by the ring links 15, constitutes a series of annular projections presenting an unsightly broken outline or raw edge, and that these edge links are so unsupported as to readily collapse.

My fabric is completed by applying to one or more edges of the piece a series of binding units 20 of a structure peculiarly adapted to firmly adhere to and stiffen the marginal series of rings without depriving the margin of adequate flexibility, and at the same time affording a substantially straight edge for the piece. Each unit is substantially transversely U-shaped and is bent up from the flat pliable metallic blank comprising, as shown in Fig. 5, a broad body portion 21 provided at one end with laterally and longitudinally directed diverging or oblique fingers or prongs 22. In this instance the opposite end of the substantially rectangular body is curved as at 23. In applying the units to the marginal rings the fingers 22 are passed through and folded over two adjacent rings 15 so that the rings are enclosed in the resultant diverging loops or folds 24. The bent prongs are shown in detail in Figs. 6 and 7. The formation of the unit is continued by transversely bending the body 21 intermediate its length to form a fold 25 and a tongue portion 26 which is clamped over upon and against the fingers 22. In Fig. 8 two of the units are shown partially engaged. The widths of the units are such that the lateral edges of adjacent

units are slightly spaced sufficiently to permit flexibility of the piece along its bound margin. The folds 25 are in longitudinal alinement along the piece, and thus form a 5 slightly edge.

In Figure 1 the units 20 are applied to one edge only of the mesh fabric. In Fig. 9 the units are applied to two opposite edges, and in Fig. 10 they are shown applied to all 10 four edges. It is obvious that the units may be applied to as many edges of the mesh as may be demanded by the particular use for which the mesh fabric is desired. When it is desired to apply the units to all 15 four edges, as shown in Fig. 10, an improved effect is attained by attaching to the corner, units 29 bent up from a blank such as shown in Fig. 11 having a substantially rectangular body 30 with one corner preferably truncated 20 as at 31, and a diagonally disposed finger 32 extending from the opposite corner. The finger 32 is bent into a loop 33 enclosing a corner ring, and the body 30 is folded back along the broken rectangular 25 lines 34 so that the resultant tongues or tongue portions 35 forms rectangular folds 36 and engage or overlap the bent finger 32.

Without departing from the spirit of my invention other modes of applying the principle thereof may be employed instead of the one explained, change being made as regards the construction herein disclosed, provided the means stated by any of the following claims or the equivalent of such 35 stated means be employed.

I claim:

1. In a metallic mesh fabric, parallel rows 40 of ring links, parallel rows of cruciform links alternating with the rows of ring links, bent prongs upon the cruciform links

engaging the adjacent ring links, and a series of binding units comprising substantially transversely U-shaped bodies enclosing a marginal row of ring links, and bent fingers upon the bodies engaging the marginal row of links. 45

2. In a metallic mesh fabric, parallel rows of ring links, parallel rows of cruciform links alternating with the rows of ring links bent prongs upon the cruciform links loosely 50 engaging the adjacent ring links, and a series of binding units comprising substantially transversely U-shaped bodies spaced from each other and overlapping a marginal row of ring links, and bent fingers upon the bodies loosely engaging the marginal row of links. 55

3. In a metallic mesh fabric, parallel rows of ring links, parallel rows of cruciform links alternating with the rows of ring links, bent prongs upon the cruciform links engaging the adjacent ring links, and a series of binding units comprising bodies provided with intermediate folds and tongue portions, and loops upon the bodies opposite 60 the folds and engaged by the tongue portions and engaging a marginal row of ring links. 65

4. In a metallic mesh fabric, parallel rows of ring links comprising uninterruptedly 70 arranged links adjacent each other, parallel rows of cruciform links alternating with the rows of ring links, bent prongs upon the cruciform links engaging the adjacent ring links, and a series of binding units including 75 diverging integral loops for the reception of the adjacent ring links.

In testimony whereof I have affixed my signature.

SAHATIEL G. MANDALIAN.
